Primary Examiner — Christian P. McLean*Assistant Examiner* — Jessica Lynn Devilbiss(74) *Attorney, Agent, or Firm* — Dhiraj Jindal; PATENT YOGI LLC(57) **CLAIM**

The ornamental design for an unmanned aerial vehicle, as shown and described.

DESCRIPTION

FIG. 1 is a top view of an unmanned aerial vehicle showing my new design;

FIG. 2 is a bottom view thereof;

FIG. 3 is a front view thereof;

FIG. 4 is a rear view thereof;

FIG. 5 is a right side view thereof;

FIG. 6 is a left side view thereof;

FIG. 7 is a top perspective view thereof;

FIG. 8 is a close-up view of the wire frame and rotor thereof; and,

FIG. 9 is a bottom perspective view thereof.

The broken lines in FIGS. 7 and 8 illustrate the periphery of the enlarged views of the unmanned aerial vehicle and form no part of the claimed design.
